UNITED STATES PATENT OFFICE.

THOMAS H. FURMAN, OF LOS ANGELES, CALIFORNIA.

PADDLE BALL.

Application filed April 10, 1924. Serial No. 705,585.

To all whom it may concern:

Be it known that I, THOMAS H. FURMAN, a citizen of the United States, residing at Los Angeles, in the county of Los Angeles and State of California, have invented new and useful Improvements in Paddle Balls, of which the following is a specification.

This invention relates to toys.

An object of this invention is the provision of a toy which may be called a paddle ball, comprising a paddle having an aperture extending through opposite faces thereof and a depending pocket communicating with the aperture and secured to the paddle, the pocket being adapted to receive a resilient ball when the same rebounds from an object, the ball being secured to the paddle by means of an elastic string.

With the foregoing object in view, together with such other objects and advantages as may subsequently appear, this invention consists in the construction and arrangement of parts hereinafter described and claimed and illustrated in the accompanying drawings, in which:

Figure 1 is a perspective view of a device embodying this invention,

Fig. 2 is a section taken on the line 2—2 of Fig. 1,

Fig. 3 is a plan view of a disc employed to secure a pocket to the paddle, and

Fig. 4 is a section taken on the line 4—4 of Fig. 3.

Referring to the drawings for a more detailed description thereof, the device of my invention is a toy comprising a wooden paddle 7 having a handle 8. The paddle has a flat under face 9 and a flat upper face 10. The body of the paddle is provided with a circular aperture 11 extending through the faces 9 and 10. A pocket 12 in the form of a net depends from the face 9 of the paddle and is secured to this face by means of an annular ring 13 having an aperture 14 of the same diameter as the aperture 11. The annular ring 13 may be of metal and is pressed out at intervals to form triangular teeth 15 which are inserted through the upper edge portion of the net and into the paddle, thereby securing the pocket or net 12 to the paddle, as clearly shown in Fig. 2.

A rubber string 17 is secured at its upper end to the paddle 7 by means of the annular

ring 13. The lower end of the rubber string 17 is attached to a resilient ball 18 which is preferably made of rubber.

In using the toy, the paddle is raised, the ball taking the direction indicated by the broken line A; the paddle is then brought down suddenly, being manipulated to strike the ball at a point B, for example. The ball then takes the direction indicated by the vertical line C and strikes the floor or ground and rebounds in a direction indicated, for example, by the broken line D, and rises above the paddle, the latter being manipulated to let the ball fall into the pocket or basket 12, the string 17 then assuming the position 17^a, shown in dotted lines.

If desired, the paddle may be turned over while the ball is in the air above the paddle and the ball caught in the basket, the latter being pushed by the ball to the opposite side of the paddle, this reversal of the pocket being allowed for by the fact that it is preferably made of flexible netting.

Variations of the above described method of use will readily suggest themselves to one who uses the toy.

This invention has been described but modifications thereof may be devised without departing from the spirit thereof, and it is to be understood that such modifications come within the scope of this invention.

What is claimed is:

1. A toy comprising a wooden paddle having an aperture extending through opposite faces thereof, a depending pocket communicating with said aperture, means for securing said pocket to said paddle, said means comprising an annular ring having teeth adapted to be pressed into the paddle, an elongated slender elastic element secured at one end to the paddle, and a resilient ball secured to the other end of the elastic element.

2. A toy comprising a paddle, there being an aperture formed in said paddle, a net forming a pocket beneath said aperture, net securing means for securing said net to said paddle, an elastic element, and a resilient ball secured to said elastic element, said net securing means serving also to secure said elastic element to said paddle.

In testimony whereof I have signed my name to this specification.

THOMAS H. FURMAN.
